UNITED STATES PATENT OFFICE.

CHARLES D. WILSON, OF TOLEDO, OHIO, ASSIGNOR OF ONE-HALF TO CATHERINE V. WILSON, OF TOLEDO, OHIO.

HAND-GRIP FOR GUNS.

1,321,173.

Specification of Letters Patent. Patented Nov. 11, 1919.

Application filed October 23, 1918. Serial No. 259,431.

To all whom it may concern:

Be it known that I, CHARLES D. WILSON, a citizen of the United States, and a resident of Toledo, in the county of Lucas and State of Ohio, have invented a certain new and useful Hand-Grip for Guns; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

This invention is particularly intended for use in connection with rapid fire guns of the Browning type.

The object of my invention is the provision of a hand grip of the class described, which is capable of being detachably mounted on the barrel and adjacent parts of a gun, which parts become highly heated during a firing of the gun, is light, strong and durable in its construction, and is capable of being subjected to very high temperatures without injury to its parts.

A further and important feature of the invention is the provision of a hand grip of the class described, which is adapted to insure the action slide or plunger of guns of the Browning type, in such manner that the rapid operating movements of the slide or plunger thereof create a forced circulation of air through the hand grip to facilitate a cooling of both the grip and the heated parts which it embraces.

The invention is fully described in the following specification, and while, in its broader aspect, it is capable of embodiment in numerous forms, a preferred embodiment thereof is illustrated in the accompanying drawings, in which,

Figure 1 is a side elevation of a portion of a gun of the Browning type with a hand grip embodying the invention mounted thereon, and with said grip and the embraced portion of the gun in central vertical longitudinal section. Fig. 2 is a section on line 2—2 in Fig. 6, with parts removed. Figs. 3, 4 and 5 are cross-sections on the lines 3—3, 4—4 and 5—5, respectively, in Fig. 1. Fig. 6 is a side elevation of the hand grip mount-

ed on a gun with the latter only fragmentarily shown. Fig. 7 is a central vertical longitudinal section of the hand grip embodying the invention. Fig. 8 is a horizontal longitudinal section thereof, and Fig. 9 is a side elevation of the inner shell or lining of the grip.

The grip forming the subject of this application is a species of the invention described and originally claimed in my application filed July 23rd, 1918, Serial No. 246,881, and as such species is the preferred embodiment of the invention, the broad claims are made in the present application.

Referring to the drawings, 1 designates the stock and 2 the barrel of a rapid fire gun of the Browning type. 3 designates the gas cylinder of such gun which is attached to the under side of the barrel and has its interior in connection with the bore of the barrel through its small passage 4. A plunger 5 operates in the cylinder and is connected with certain operating parts 75 (not shown) of the gun mechanism by a slide 6, which is connected to the plunger by a stem 7. A frame bar 8 is removably fixed to the stock 1 and extends forward therefrom and has its forward end provided with an off-set portion 9 that is provided with an opening in which the rear end of the gas cylinder 3 is mounted. These parts are all common to the Browning gun and need not therefore be specifically described.

The hand grip embodying my invention is intended to embrace the rear end portion of the barrel 2 and the adjacent portions of the cylinder 3, slide 6 and frame bar 8 at the point where the gun is customarily gripped when in use or when being carried. This hand grip comprises a lining or inner shell 10, preferably of aluminum, and an outer shell 11, preferably of vulcanized fiber, the inner shell being shaped to adapt it to be slipped longitudinally over the barrel 2, cylinder 3, plunger slide 6 and frame bar 8 with its rear end in abutment with the stock and a shoulder portion of the frame bar 8 with its forward end set against the under side of the cylinder 3 and forming an air circulating space around the remainder of said cylinder and the barrel 2. The engage-

ment of the rear end of the hand grip with the stock is such as to provide an air circulating space between the sides and top portion of the grip and the stock or inclosed portion of the gun.

The shell 10 is substantially U-shape in cross-section with its terminal side edge portion turned inward over the barrel in spaced relation thereto and preferably terminating in spaced relation to each other to form the longitudinal top opening 12. The shell 10 is provided with longitudinally spaced cross ribs 13 in its bottom portion which form bearings for the frame bar 8 and space such bar from the major bottom portion of the shell, as shown in Figs. 1 and 7. The shell is also provided at its forward end portion with longitudinally spaced bearings or rests 14 for the cylinder 3, the rear rest being vertically spaced from the bottom of the shell to permit the circulation of air thereunder.

The outer shell 11 entirely closes the inner shell fitting closely thereto at its ends and being spaced from the inner shell intermediate its ends to provide air circulating chambers or spaces 15 therebetween. It is preferable to slightly contract the bulged side portions of the shell above the bottom thereof, as best shown in Fig. 4, to better facilitate a firm gripping of the shell by the hand of the operator. It is preferable, but not necessary, to provide the inner shell

10 with longitudinally spaced vertically extending ribs 16, which effect a positive spacing of the two shells at the sides and bottom portions thereof. It is also preferable to extend the ribs 16 up over the inturned edges of the inner shell to provide air escape openings or passages 17 between the lapped upper edge portions of the respective shells. Air is admitted to the circulating spaces between the shells through a plurality of openings 18 in the lower portions of the outer shell 11 (see Figs. 4 and 6).

The shells 10 and 11 are secured together, in the present instance, by rivets 19 at their ends and by similar rivets (not shown) disposed along the top inturned edge portions thereof through the spacing ribs of the inner shell. The hand grip is secured to the frame bar 8 by a screw 20 and also by a cross screw or bolt 21.

My hand grip when applied to a gun provides an air circulating space lengthwise through the grip around the inclosed gun parts with such space open at both ends and also along its top to the atmosphere.

Upon the firing of the gun the rapid reciprocation of the slide 6 within the grip causes a forced circulation of a cooling air through the grip and a consequent cooling of the heated parts, it being understood that after each explosion a portion of the cre-

ated gas enters the cylinder 3 from the gun barrel in advance of the plunger 5, and drives such plunger rearward. It is found in practice that a considerable current of air is created through the hand grip by the pumping action of the plunger on its slide.

In addition to cooling the hand grip and inclosed parts by the forced circulation of air therethrough the cooling of the grip is also facilitated by the circulation of air between the inner and outer shells 10 and 11 thereof, through the side spaces 15, thus preventing liability of burning the hands of the operator.

It is found in practice that particular advantage is obtained from making the inner shell of aluminum as it not only lightens the handle and provides a strong frame or reinforcement for the outer fiber shell, but facilitates a cooling of the grip over other materials which have been used. It is also found that the use of vulcanized fiber as the material for the outer shell is important, as such material is a good heat insulator, is capable of standing intense heat without charring and cracking, and also of being dipped in water when heated and of being soaked for several hours without cracking or warping. It is also capable of resisting hard knocks and pressure without breaking. All of these qualities are of the utmost importance in a hand grip for fire arms.

I wish it understood that my invention is not limited to any specific construction or arrangement of the parts, as it is capable of numerous modifications without departing from the spirit of the claims.

Having thus described my invention, what I claim as new and desire to secure by Letters Patent is:—

1. A hand grip of the class described, comprising inner and outer shells having portions spaced to provide air passages, one of said shells having inlet and outlet openings to said passages.

2. A hand grip of the class described, comprising a shell of heat insulating material open at its ends, and a lining of a different material from said shell coöperating therewith to form air spaces between the sides of the lining and shell, which spaces are open to the atmosphere.

3. A hand grip of the class described, comprising a heat insulating shell open at its ends and adapted to fit over a portion of a gun, and a lining of aluminum within said shell and coöperating therewith to form air circulating passages which are open to the atmosphere.

4. A hand grip of the class described, comprising an inner shell of aluminum adapted to provide an air circulating space around the article on which mounted, and an outer shell of vulcanized fiber carried by

said inner shell and coöperating therewith to provide air passages therebetween which are open to the atmosphere.

5. A hand grip of the class described, comprising an inner shell open at its ends and top to the atmosphere, and adapted to provide an air circulating space around an article on which mounted, and an outer shell mounted on said inner shell and having portions spaced to provide air passages therebetween, which passages are open at top and bottom to the atmosphere.

6. A hand grip of the class described, comprising an inner shell of aluminum open at its ends to the atmosphere, and adapted to provide an air circulating space around an article on which mounted, and an outer shell of vulcanized fiber mounted on said inner shell and coöperating therewith to form air spaces between portions thereof, which spaces are open at top and bottom to the atmosphere.

7. A hand grip of the class described, comprising an inner shell open at its ends and substantially U-shape in cross-section, with its terminal edges turned inward toward each other and terminating in spaced relation, and an outer shell of heat insulating material mounted on said inner shell and coöperating therewith to form air circulating spaces between the walls of the two shells which are open at top and bottom to the atmosphere.

8. A hand grip of the class described, comprising inner and outer shells open at their ends and substantially U-shape in cross-section with their terminal edges turned inward toward each other, said shells having portions spaced apart to provide air circulating passages therebetween which are open at their top and bottom to the atmosphere, and one of said shells having ribs projecting therefrom within said passages to serve as spacing means for the other shell.

9. A hand grip of the class described, comprising an inner shell of aluminum open at its ends and substantially U-shape in cross-section and having its terminal edges turned inward toward each other, and an outer shell of vulcanized fiber fitted to said inner shell, said shells having portions spaced intermediate their ends to provide air circulating passages which are open at top and bottom to the atmosphere.

10. The combination with a gun, having a gas cylinder in connection with the interior of the gun barrel, and having an action slide with plunger operating in said cylinder, of a hand grip embracing a portion of each said barrel, cylinder and slide and forming an air circulating space lengthwise thereof, the operation of said slide and plunger effecting a forced circulation of air through the hand grip.

11. The combination with a gun, having a gas cylinder in connection with the interior of the gun barrel, and having an action slide with a plunger operating in said cylinder, of a hand grip embracing a portion of said barrel, cylinder and slide and forming air circulating spaces lengthwise thereof, the operation of said slide and plunger effecting a forced circulation of air through the hand grip, said grip having inner and outer shells with portions thereof spaced to form air passages therebetween with such passages open to the atmosphere.

12. The combination with a gun, having a reciprocably movable actuating member, of a hand grip for embracing a part of said gun and member, said grip comprising an inner metal shell through which a circulation of cooling air is pumped by the action of said member, and an outer shell of vulcanized fiber mounted on said inner shell and coöperating therewith to form air circulating spaces between portions thereof, which spaces are open to the atmosphere.

13. The combination with a gun, having a gas operated action slide at one side of its barrel, of a heat insulating shell forming a hand grip around portions of the barrel and slide, and also forming an air passage lengthwise thereof which passage is open to the atmosphere, and through which a forced circulation of air is created by an operating movement of said slide.

14. The combination with a gun, having a gas cylinder of a supporting frame member therefor, and an action slide operated by gas pressure within said cylinder, of a heat insulating shell removably fitted over said parts and forming a heat insulating hand grip, and providing an air passage around portions of said parts and lengthwise thereof, which passage is open to the atmosphere and through which a forced circulation of air is effected by an operation of said action slide, and means for rapidly securing the shell to said frame member.

15. The combination with a gun having a gas operated action slide at one side of its barrel, of a heat insulating hand grip embracing portions of the barrel and slide and forming an air passage lengthwise thereof, which passage is open at opposite ends to the atmosphere and through which a forced circulation of air is induced by an operating movement of the action slide, said grip having inner and outer shells which coöperate to form air passages therebetween that are open to the atmosphere.

16. The combination with a gun having a gas operated action slide at one side of its barrel, of a heat insulating hand grip embracing portions of the barrel and slide and forming an air passage lengthwise thereof which passage is open at opposite ends to the atmosphere and through which a forced

circulation of air is induced by an operating movement of the action slide, said grip having an inner shell of aluminum and an outer shell of heat insulating material which shells coöperate to form air passages therebetween that are open to the atmosphere.

17. A hand grip for guns comprising a shell of substantially U-form in cross-section, a lining for said shell spaced there-

from except at its ends and edge portions to form air spaces between the shell and lining at the sides thereof, which spaces are open to the atmosphere, said shell having its side portions inwardly depressed above its bottom edges to facilitate a firm hand gripping thereof. 15

In testimony whereof I have hereunto signed my name to this specification.

CHARLES D. WILSON.
